UNITED STATES PATENT OFFICE.

CHARLES APPE, OF BROOKLYN, NEW YORK.

DESIGN FOR A TRAFFIC SIGN.

Application filed May 18, 1923. Serial No. 6,204. Term of patent 7 years.

To all whom it may concern:

Be it known that I, CHARLES APPE, a citizen of the United States, residing at Brooklyn, in the county of Kings and State of New York, have invented a new, original, and ornamental Design for a Traffic Sign, of which the following is a specification, reference being had to the accompanying drawing, forming part thereof.

In the drawings:—

Figure 1 is a front elevation.

Figure 2 is a top edge view.

Figure 3 is a side edge view.

I claim:—

The ornamental design for a traffic sign, as shown.

CHARLES APPE.
